UNITED STATES PATENT OFFICE.

ELMER R. WILLIAMS, OF SPRINGFIELD, MISSOURI, ASSIGNOR OF ONE-EIGHTH TO
GEORGE A. MESSICK, ONE-EIGHTH TO CLYDE GAULT, AND ONE-EIGHTH TO
THOMAS H. BROWNS, ALL OF SPRINGFIELD, MISSOURI.

WATER-HEATING SYSTEM.

Application filed December 24, 1923. Serial No. 682,515.

To all whom it may concern:

Be it known that I, ELMER R. WILLIAMS, a citizen of the United States, residing at Springfield, in the county of Greene and State of Missouri, have invented certain new and useful Improvements in Water-Heating Systems, of which the following is a specification, reference being had to the accompanying drawings.

10 This invention relates to certain new and useful improvements in water heating systems and has for its primary object the provision of novel means whereby water may be rapidly heated to a high degree for consumption.

Another object of the invention is to provide a device of the above character wherein the means provided to produce the desired result is of a most simple and practical construction so as to meet with all of the requirements for a successful commercial use.

With the above general objects in view, and others that will become apparent as the nature of the invention is better understood, 25 the same consists in the novel form, combination and arrangement of parts hereinafter more fully described, shown in the accompanying drawing and claimed.

In the drawing, Figure 1 shows what is 30 believed at present to be the preferred embodiment of the invention, partly in vertical section, and partly in side elevation, and Figure 2 is a sectional view showing one form of thermostat control of the heater.

35 Referring more in detail to the drawing, the invention embodies a lower or inlet reservoir 5 having an inlet 6 for connection with any suitable source of water supply, such as a city main, and an upper or outlet reservoir 40 7 having an outlet 8 connecting with a faucet 9 for controlling the discharge of heated water at the point of consumption.

Although it is not essential to the invention, the reservoirs are shown as preferably 45 constructed by dividing a tank 10 into two compartments by means of a horizontal partition 11 which is disposed nearer the top of the tank 10 than to the bottom thereof so that the reservoir 5 will be of greater capacity than the reservoir 7.

A water circulating connection is provided between the bottom of the reservoir 5 and the top of the latter, as at 12, this connection including a coil 13 adapted to be heated by

any suitable means, such as a gas burner 14. 55 A water circulating connection is also provided between the lower reservoir 5 and the outlet reservoir 7, as at 15, and they include a second coil 16 also heated by the burner 14. The lower portion of the tank 10 is 60 preferably provided with a central chamber 17 in which the coils are positioned. The upper wall of this chamber is provided with a central opening communicating with an axial flue 18 provided for the exit of products of combustion from the burner 14.

The coil 16 has its inlet connected by means of a pipe 19 with the upper reservoir 7 so that water circulating connections are provided from the bottom of said reservoir to the top thereof which include the auxiliary coil 16. It will be seen that when the burner 14 is lighted and the faucet 9 is closed water will pass from the upper reservoir 7 through pipe 19 and coil 16 to pipe 15 and then back into the upper reservoir.

However, when the faucet 9 is opened there would be a tendency of the water to flow from the inlet of the coil 16 through pipe 19 into the upper reservoir 7, and in order to prevent this, a check valve 20 is employed between the coil 16 and the reservoir 7 in the pipe 19, which check valve will obviously, however, permit circulation of the water from reservoir 7 through pipe 19, coil 16 and pipe 15 back to said upper reservoir. In order that over-heating of the water may not occur and that additional heat may be furnished automatically when the heat of the water becomes too low, a control valve 21 for the burner 14 may be operatively connected with the expansible element 22 of a thermostat in any well known or preferred manner, which thermostat is associated with the pipe 15 near the inlet of the coil 16. One form of this arrangement is shown in Figure 2 in which the gas inlet pipe is indicated at I and an outlet pipe at O, this outlet pipe communicating with the burner 14 and the thermostat fitting T which is inserted in the right hand branch of the pipe 15 has passages P and P' connecting with the inlet I and outlet O and between these passages, communication is established through the valve 21.

The thermostatic element 22 controlling the operation of this valve is located in a conduit C connecting adjacent ends of the

right hand section of the pipe 15 so that it is constantly subjected to the passage of water through this pipe.

In operation, the water enters the reservoir 5 through pipe 6 and overflows through pipe 15 as well as pipe 12, so as to fill the coils 13 and 16 and the reservoir 7. With the faucet 9 closed and the burner 14 lighted, a circulation of water is had from reservoir 5 through the right hand portion of pipe 15 and coil 16 to the left hand portion of pipe 15 and thence into the upper reservoir 7, through pipe 19 past the check valve 20 into the coil 16 and thence through the left hand portion of pipe 15 back to said upper reservoir. In addition, the water passes from the bottom of the lower reservoir 5 through coil 13 and pipe 12 into the top of the reservoir 5. When the faucet 9 is opened all water that flows therethrough must pass through coil 16 into the upper reservoir 7 and thence into the outlet pipe 8. Thus, water which has previously been warmed by passing through the circulating connections 12 must pass from reservoir 5 through pipe 15 and be heated a second time in passing through coil 16 before flowing to the outlet piping 8. It will be obvious that when water from the right hand branch of the pipe 15 is passing through the coil 16 to the reservoir 7, this water will be cooler than that circulated through the coil by the pipe 19 and accordingly during such passage, the action of the heater will be greater.

From the foregoing description it is believed that the construction and operation, as well as the advantages of the present invention, will be readily understood and appreciated by those skilled in the art.

Minor changes may be made without departing from the spirit and scope of the invention as claimed.

What I claim is:—

- 45 1. In a water heating apparatus, a lower reservoir, an upper reservoir located thereabove, an inlet pipe leading into the bottom of the lower reservoir, a chamber within the lower portion of the lower reservoir having an outlet flue extending through the upper reservoir, heating means at the bottom of the chamber, a coil located within said chamber and having one end communicating with the lower reservoir at the bottom thereof and its other end communicating with the upper portion of the lower reservoir, a pipe within the lower reservoir communicating at one end with the bottom of the upper reservoir and having its other end opening into the lower reservoir near the top thereof, and a coil connected with said second named pipe and extending about the first named coil and communicating with the top of the upper reservoir.
- 65 2. In a water heating apparatus, a casing,

a partition within the casing dividing the same into a lower reservoir and an upper reservoir, an inlet pipe at the bottom of the lower reservoir, a shell located within the lower portion of the lower reservoir and constituting a heating chamber, heating means at the bottom of said chamber, a flue leading from said chamber through the top of the upper reservoir, an outlet pipe at the top of the upper reservoir, a coil within said chamber having one end communicating with the lower portion of the lower reservoir and having its other end extended laterally through the casing and extending exteriorly thereof and communicating with the top of the lower reservoir, a U-shaped pipe having one vertical leg located within the lower reservoir and communicating with the bottom of the said upper reservoir and its other leg located within the lower reservoir and terminating short of said partition, the bight portion of said U-shaped pipe being located below said chamber, and a second coil within the chamber in surrounding relation to the first named coil and having one end connected with said bight portion and its other end extended laterally through the casing and connected with the top portion of the upper reservoir.

3. In a water heating system, upper and lower reservoirs and a heater, an inlet connection at the lower end of the lower reservoir, a valved outlet connection for the upper end of the upper reservoir, a circulating connection between the upper end of each of said reservoirs and the lower end thereof each embodying a coil subjected to the action of said heater and a connection between the upper end of the lower reservoir and the circulation connection of the upper reservoir between the lower end of the upper reservoir and said coil.

4. In a water heating system, upper and lower reservoirs and a heater, an inlet connection at the lower end of the lower reservoir, a valved outlet connection for the upper end of the upper reservoir, a circulating connection between the upper end of each of said reservoirs and the lower end thereof each embodying a coil subjected to the action of said heater and a connection between the upper end of the lower reservoir and the circulation connection of the upper reservoir between the lower end of the upper reservoir and said coil, the circulating connection for the upper reservoir including a check valve opening toward the coil and located between the inlet end of the circulating connection and a connection between said circulating connection with the upper end of the lower reservoir.

5. In a water heating system, upper and lower reservoirs and a heater, an inlet connection at the lower end of the lower reservoir, a valved outlet connection for the up-

per end of the upper reservoir, a circulating connection between the upper end of each of said reservoirs and the lower end thereof each embodying a coil subjected to the action of said heater and a connection between the upper end of the lower reservoir and the circulation connection of the upper reservoir between the lower end of the upper reservoir and said coil, the connection be-

tween the upper end of the lower reservoir 10 and the circulating connection of the upper reservoir including a thermostatic control for the heater operated by the temperature of the water passing therethrough.

In testimony whereof I hereunto affix my 15 signature.

ELMER R. WILLIAMS.
